UNITED STATES PATENT OFFICE.

GEORGE RUNNEBAUM, OF WESTPOINT, TENNESSEE.

BED SUPPORT.

1,420,755.

Specification of Letters Patent. Patented June 27, 1922.

Application filed January 18, 1922. Serial No. 530,187.

To all whom it may concern:

Be it known that I, GEORGE RUNNEBAUM, a citizen of the United States, residing at Westpoint, in the county of Lawrence and

5 State of Tennessee, have invented certain new and useful Improvements in Bed Supports, of which the following is a specification, reference being had to the accompanying drawings.

10 It is difficult and tedious to move beds, when sweeping or when using a vacuum cleaner, or when it is desired to get on the side of the bed nearest the wall, especially when a person is lying ill. Very often it is necessary to get between the bed and the wall, to administer medicine to the patient, and also to sweep or use a vacuum cleaner under the bed nearest the wall, and when moving the bed the rollers for the legs of 15 the bed are very apt to catch in the rug or carpet, in the first instance rumple the rug, and the feet or rollers are very apt to rip the carpet, especially if the bed is pushed, instead of being lifted bodily, and in this 20 case the corner will catch in the floor covering. Furthermore rollers or feet of the bed will also scar the floor, if not supplied with a floor covering.

Therefore, it is the purpose of the present 30 invention to provide a bed support, wherein the construction and arrangement thereof are such as to permit the bed to be easily moved, to permit access to the side of the bed nearest the wall, either to attend to the 35 patient, or for sweeping or using a vacuum cleaner under the bed.

Still another purpose is the provision of a bed support comprising guiding supports at the opposite ends of the bed, in combination 40 with sliding supports carrying the bed proper and engaged with the guiding supports, so that when it is desired to have access to the side of the bed nearest the wall for any purpose whatever, the sliding bed 45 supports may be moved laterally in their guiding supports, and after attending to the patient or sweeping or otherwise cleaning the floor adjacent the side of the bed nearest the wall, the bed may be easily returned 50 to its original position, simply by pushing upon the side of the bed.

A further purpose is the provision of a guiding support provided with insert rubber blocks or shoes, to prevent slipping of 55 the guiding supports, which are joined by a longitudinally extending connector.

It is also the aim to provide improved means carried by the sliding supports to be engaged by the bed, in order to detachably support the bed in position.

60

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed.

65 The invention comprises further features 70 and combination of parts, as will be hereinafter set forth, shown in the drawings and claimed.

In the drawings:—

75 Figure 1 is a view in side elevation showing the bed mounted upon the improved support;

Figure 2 is a sectional view through the same;

80 Figure 3 is a plan view of the supports for the opposite ends of the bed joined by the connector;

Figure 4 is a view longitudinally through the support for one end of the bed;

85 Figure 5 is a detail view of one end of one of the supports;

Figure 6 is a detail view of the sliding support.

Referring to the drawings, 1 and 2 designate supports for the opposite ends of a 90 bed. Each support is provided with a longitudinal channel 3, between the side walls of which the ball bearing mounted rollers 4 are mounted. These rollers are engaged by the horizontal rail 5 of a sliding 95 support 6, on the lower end of the leg 7 of which a roller 8 is mounted. This roller is adapted to engage the floor, when the bed is moved laterally, so that access may be had to the side of the bed nearest the wall. 100 The horizontal rail of the sliding support is of a width to engage in the channel of its support, and is provided with a plurality of sockets 9 to receive the lugs 10 of the bed supports proper 11. These bed supports 11 are thick enough to engage in the restricted or upper narrow portion of the channel, in order to assist in guiding the sliding support from between the opposite walls of the main support. The supports 11 105 have upwardly extending lugs 12, which engage the socket 13, (which usually receive

roller casters not shown) for the bed, and in this way the bed rests upon the guiding supports. When the lugs 12 enter the socket 13, the lower end surface of the legs of the 5 bed rest upon the shoulders 14, to hold the bed in position and to limit the insertion of the lugs 12 in the sockets 13.

The opposite ends of each support 1 and 2 are provided with legs 15 having trans- 10 versely disposed dovetailed channels 17, to receive the correspondingly shaped rubber shoes or blocks 18, which have their under faces corrugated to prevent them from slipping. The end face of one of the legs 15 of each support 1 and 2 has a downwardly extending channel 19, to receive the legs 7 of the sliding support when the same is closed.

The adjacent faces of the supports 1 and 20 2 are provided with lateral lugs 20, which are recessed at 21 and engaged by the recessed ends 22 of the transverse pieces 23, which are carried by the longitudinally extending connecting rail 24. It is obvious 25 that any length of connecting rail may be used, so as to vary the length of the bed supports. By means of the connecting rail 24 and the transverse pieces 23 together with the lugs, the opposite supports 1 and 2 are 30 maintained in their proper positions relatively to the bed 25.

Suitable foot engaging buttons 26 are detachably connected at 27 to the horizontal rails of the sliding supports. These buttons have ends 28, which overlie the walls on opposite sides of the channels of each support 1 and 2. These foot engaging buttons may be engaged by a foot, so as to move

the sliding supports laterally and also the bed.

The invention having been set forth, what is claimed as being useful is:—

1. In a bed support, a pair of opposite guiding supports, means connecting said supports, according to the length of the 45 bed to be supported, sliding supports mounted in the guiding supports and being movable transversely and having means to be engaged by the legs of the bed for supporting the same, said sliding supports having a depending leg at one end provided with a roller to engage the floor, and one end of each guiding support having a vertical channel to receive the leg of the guiding support. 50

2. In a bed support, a pair of guiding supports, a connector therefor, to hold them in position according to the length of bed to be supported, each of said guiding supports having depending feet provided with 60 corrugated rubber insert shoes, one end of the guiding support having a vertical channel, a sliding support anti-frictionally mounted in the guiding support for horizontal movement, said sliding support having means to be engaged by the legs of the bed to support the same, said sliding supports having legs to enter the vertical channels of the guiding supports, said legs having surface engaging members, to support 70 the sliding support and the bed when moved laterally, and means carried by the sliding supports to move them. 65

In testimony whereof I hereunto affix my signature.

GEORGE RUNNEBAUM.
